UNITED STATES PATENT OFFICE.

WILLIAM E. WILLIAMS, OF CHICAGO, ILLINOIS.

MACHINE FOR CRIMPING METAL PLATES OR SHEETS.

SPECIFICATION forming part of Letters Patent No. 510,559, dated December 12, 1893.

Application filed September 21, 1892. Serial No. 446,456. (No model.)

To all whom it may concern:

Be it known that I, WILLIAM E. WILLIAMS, a citizen of the United States of America, residing at Chicago, in the county of Cook and State of Illinois, have invented a certain new and useful Machine for Crimping Metal Plates or Sheets, of which the following is a specification.

In the accompanying drawings, wherein like reference letters indicate like parts, Figures 1. to 5., inclusive, represent the machine, and Fig. 6. the finished product—Figs. 1., 2., 3. showing the machine with its clamping-bar and crimping-jaws thrown back, ready to receive the blank plate; Fig. 4. showing the clamping-bar down before the jaws are closed on the plate; and Fig. 5. showing the position of the parts at the moment of completing a crimp. Fig. 1. is a side elevation; Fig. 2., a top plan; Fig. 3., an end elevation; Fig. 4., a side elevation; and Fig. 5. a top plan; and Fig. 6. a metal web for car-wheels, crimped on my improved machine.

In a patent granted to me December 31, 1889, No. 418,634, I described and illustrated a car-wheel of my invention, having a web of sheet or plate metal crimped into the form shown here in Fig. 6.—the corrugations being narrow and deep at the hub, and widening out and running down to a common plane; or, in other words, "running out" at the rim. The machine which forms the subject of my present application was designed to facilitate the manufacture of such crimped or corrugated webs, by providing means whereby a suitable sheet or plate of metal can be readily crimped into uniform corrugations, and at the same time drawn into circular form, adapting it for use for the purpose indicated.

The invention consists in the several mechanical combinations and devices summarized in the claims.

The construction and operation of the machine may be described as follows:

Upon a suitable table T., I secure a cast-iron or cast-steel bed-plate B., having upwardly-projecting side-lugs b. From these lugs forward, the bed-plate tapers in width to or nearly to its front end, where it is provided with a vertical bolt-hole b'. On the upper surface of the plate, extending from a point at or near the rear edge of the bolt-

hole to a point near the side-lugs, is a raised anvil or crimping-block A., the form of which will be clearly understood by comparing the three views of it in Figs. 1., 2., 3. In general terms, it consists of two wedge-shaped elevations a. a', formed on the bed-plate—the elevation a. being in the form of a wedge lying on its side with its butt to the rear, and the elevation a' rising out of the part a. in the form of a wedge lying on its edge with its base to the rear.

The operation of the machine is to crimp the blank sheet over and around the part a' into the angle formed between the vertical walls of a' and the inclined top surface of part a. The means by which this is done are as follows: A rocking-plate or block D., journaled to the lugs b. b., extends horizontally backward, as shown at d. (Fig. 2), thence upward to form a standard and clamping-bar, as shown at d'. d'. (Figs. 1. and 3.), and thence forward to form a locking-bolt, as shown at d'. (Figs. 1. and 2.). The device D. may thus be turned upward and backward into the open position shown in Figs. 1., 2., 3., or forward and downward into the closed position shown in Figs. 4. and 5., in which latter case, the locking bolt d'. will extend through the hole b' and may be fastened by a key d'. (Fig. 4.). A portion d'. of the front face of the standard d'. is made wedge-shaped (see Fig. 3.), to correspond to the top surface of the anvil a', and is projected somewhat forward of the body of the standard (see Fig. 1), so as to come squarely down upon the top of the anvil a' when the standard is lowered to the position shown in Figs. 4. and 5., and thus act as a clamping-bar to hold the metal sheet firmly in place on the anvil during the crimping operation. At the sides of the standard d'. are two pivoted crimping-jaws C. C', each provided with a strong handle C'. The front faces of these jaws are wedge-shaped, as shown in Fig. 3., and are adapted to fit against the side faces of the anvil a'. The two jaws are pivoted at top and bottom to the pivoted part D., as shown at c. c'. (Fig. 3.), their pivots being in line with the front corners of the clamping-bar d', so that when the latter is brought down upon the anvil, and the handles C'. are then brought to a horizontal position, as shown in Fig. 5., the faces of the jaws will

fit accurately against the sides of the anvil. It will, of course, be understood that a sufficient space or clearance is left between the anvil and the clamping and crimping faces 5 d^2 . C. to admit the metal sheet or plate which is to be crimped. A graduated gage-plate G. projects from the side of the bed-plate or the table, by which the operator can measure the distance to which it is necessary to feed the 10 blank sheet forward to produce crimps of the proper size and of uniform dimensions. The sheet which is to be crimped will be drawn into a circle by the crimping-operation, and should therefore be cut of suitable length to form the 15 circle, and of a width somewhat more than equal to the length of the anvils a' , the excess being preliminarily turned down at right angles to the body of the sheet to form a narrow flange along its lateral edge. 20 In operating the machine, the two handles C². are brought together to open the jaws, and the device D. is then turned back to the position shown in Figs. 1., 2. and 3. The end of the sheet is then placed upon the anvil, with the 25 flange of the sheet down and against the inner end of the anvil, and the lateral edge of the sheet parallel with the edge of the guide-plate. The device D. is then turned down to clamp the sheet to the anvil, and the locking-bolt d^3 . is keyed in position, as shown in Fig. 30 4. The operators then grasp the two handles C². and force them apart and downward to the position shown in Fig. 5., thereby causing the jaws C. C'. to bend the metal down at each 35 side of the anvil, and form a permanent crimp in the sheet. The handles are then raised, the device D. turned back to the position shown in Figs. 1., 2. and 3., the sheet fed along a distance equal to the width of the outer end 40 of the crimp already formed (which the gage

will indicate), and the operation repeated. The final result is a crimped sheet in the form shown in Fig. 6., having a narrow flange around its outer edge at right angles to the plane of the circle. The meeting edges are 45 then brazed, soldered, or otherwise secured together, the hub cast in and the rim bolted on to finish the wheel.

Having thus described my invention, what I claim as new, and desire to secure by Letters 50 Patent, is—

1. In a crimping machine, the crimping-block A., constructed with the wedge-shaped or inclined base a , and the wedge-shaped anvil a' . formed upon the inclined face of the base a ; 55 in combination with means for bending the metal to be crimped upon and in conformity to the anvil a' ; substantially as described.

2. In a crimping machine, the combination of the wedge-shaped anvil a' . with a rocking 60 clamping-plate having the wedge-shaped face d^2 ., and with crimping-jaws pivoted to the rocking plate in line with the corners of the face d^2 ; substantially as described.

3. In a crimping machine, the combination 65 of the crimping-block A, constructed with the wedge shape or inclined base a , and the wedge shaped anvil a' ; with the pivoted clamp D, having a wedge shaped face d^2 adapted to come in contact with and clamp the blank 70 upon the anvil; and crimping jaws pivoted to the clamp in line with the corners of the face d^2 , whereby the blank held upon the anvil may be crimped against the sides and assume the form of the anvil; substantially as de- 75 scribed.

WM. E. WILLIAMS.
